HOT TOP LINING

Walter W. Urmetz, Parma, Ohio, assignor to The Ferro Engineering Company, Cleveland, Ohio, a corporation of Ohio

Application October 22, 1934, Serial No. 749,402

3 Claims. (Cl. 22—147)

This invention relates to improvements in hot top linings, that is to say linings built up of refractory blocks fitted together at their edges so as to cover the inner walls of metallic casings.

One of the objects of the invention is the provision of an improved arrangement of lining blocks for such hot tops as are of generally rectangular form with upwardly tapered inner walls.

Another object is the provision of a lining for this type of casing wherein the cubical contents of the lined hot top for a given height will be greater than heretofore.

Another object is the provision of an improved lining which will permit a reduction in the height of a hot top for a given content of metal, thereby saving in material for the casing as well as in lining material.

A further object is the provision of a proportionately larger opening at the bottom of the hot top in order to improve the feeding ability of the hot top, particularly on small molds.

Still another object is the provision of a lining which shall be thinner at the bottoms of the corners, and will thereby require less material in the bottom rings, which must register with the bottom of the regular lining.

Other objects and features of the invention will appear as I proceed with the description of that embodiment of the invention which, for the purposes of the present application, I have illustrated in the accompanying drawings, in which

Fig. 1 is a vertical transverse sectional view of a hot top casing, with lining elements embodying the present invention.

Fig. 2 is a fragmental top plan view of the lining elements alone in their assembled relation.

Figs. 3 and 4 are elevational and plan views respectively of one of the side lining elements.

Figs. 5 and 6 are similar views of one of the corner lining elements.

Fig. 7 is a view similar to Fig. 2 but showing a known construction.

Fig. 8 is a vertical sectional view of a casing and lining corresponding to that illustrated in Fig. 7, the view being taken substantially upon the line 8—8 of Fig. 7.

Figs. 9 and 10 are elevational and top plan views respectively of the corner blocks shown in Fig. 8.

Fig. 11 is a view corresponding to Fig. 8, but showing the corner lining blocks illustrated in Figs. 1 and 2.

Figs. 12 and 13 are elevational and top plan views respectively of the latter corner blocks.

Fig. 14 is a diagrammatic plan view showing

the difference in content at one corner only of the same hot top when lined according to Figs. 1 to 6 inclusive, and when lined according to Figs. 7 to 10 inclusive.

Fig. 15 is a perspective view looking in the direction of arrow 15, Fig. 14, showing the increase in volume of a hot top at one corner when the lining of Figs. 1 to 6 inclusive is used.

The present invention has to do with linings for rectangular hot tops of the type illustrated in Charman and Darlington Patent 1,804,203, issued May 3, 1931. It is frequently important to provide as much capacity as possible for a given height of hot top. The present invention increases the content of the hot top, its effect being greatest comparatively in the case of hot tops intended for use with molds of relatively small horizontal dimensions. The increase in content of the hot top arising from the use of the present invention is located principally at and near the bottom of the hot top, which is desirable in that it decreases the overhang of the hot top lining block at the corners of the hot top, thus permitting not only greater volume of metal per inch of hot top, but also greatly reducing the distance from the corners of the mold with which the hot top is being used, to the inside of the corners of the hot top, thus facilitating more efficient feeding of the ingot below the hot top. In other words there is much less constriction between the lower extremities of the hot top and the walls of the ingot mold within which the hot top is placed. I accomplish this result by the expedient of making the corner blocks straight and putting the taper into the side blocks, instead of employing the opposite arrangement as in Patent 1,804,203 above referred to. In order to point out the invention more clearly than it would be possible to do otherwise, I have illustrated the known construction in Figs. 7, 8, 9 and 10, and have thereby laid the basis for the diagrammatic showing of Figs. 14 and 15, to which reference will be made presently.

Referring now to Figs. 1 to 6 inclusive, a metallic hot top casing is illustrated at 20. At its lower end this casing is provided with an internal ledge 21 upon which the upper lining elements are supported. The inner and lower surfaces of the ledge are covered with a bottom ring 22 of refractory material, a new bottom ring being used for each heat. These rings are attached to the casing by wire clips 23, as more particularly described in Charman Patent 1,849,292. A wiper strip 24 serves to close the clearance be-

tween the hot top and the inner surface of the mold, such wiper strips being described and claimed in Charman and Darlington Patent 1,804,207.

5 The casing 20 is generally rectangular in form, although the corners may be rounded as shown. The inner surfaces of the casing are tapered upwardly in accordance with the usual practice. The lining above the ledge 21 consists of refractory blocks which are made in such sizes and shapes as to fit the internal surfaces of the casing and be retained against inward movement by their own interengagement. As herein illustrated I employ on each side surface of the casing lower and upper lining blocks 24 and 25 respectively. Each of these blocks is tapered upwardly, that is to say, the side edges of the blocks are inclined upwardly toward each other, both at the same angle. These side edges are also beveled inwardly, as appears clearly in Figs. 3 and 4. The inner face of each of the blocks 24 and 25 is flat, and each of these faces, or the two together, may be said to have the shape of a symmetrical trapezoid, the upper edge of which is shorter than the lower edge.

20 In the corners of the casing I use corner blocks 26, all of which may be identical in shape and size. The inner surface of each of these corner blocks is a rectangle. The side or lateral edges 30 are beveled off inwardly at the proper angle to make a precise fit with the beveled edges of the blocks 24 and 25. The outer surfaces of blocks 26 are of course made to conform with the corner surfaces of the casing, which in the present instance are rounded.

35 The procedure in assembling the lining elements is to first place the side blocks 24 in the casing, then to slide the lower corner blocks 26 into place, when the lower lining course will be 40 locked in position. The four side blocks 25 of the upper course are then put into the casing, and finally the upper corner blocks 26 are slipped into position between adjacent blocks 25, which locks the upper course blocks in place. The 45 joints between blocks are then usually filled with heat-resisting cement in the manner well known in the art.

50 Referring now to Figs. 7 to 10 inclusive, where I have illustrated a lining arrangement previously used for a rectangular hot top, the side blocks 27 of the lining are straight, that is their side edges do not taper as do the side edges of the blocks 24 and 25 of the present invention. The 55 corner blocks 28 and 29 however are tapered and the two blocks are consequently of different size. The side edges of all blocks are beveled in order to hold all of them in position.

55 It will be observed by comparison of Figs. 8 and 11 that the lower surface of corner block 29 has a greater dimension in a diagonal direction than that of lower corner block 26, in other words corner block 29 extends farther into the hot top space than does block 26. In Figs. 7 and 8 I

have marked the lower forward edge of the block 29 with the reference character *a*. The lower forward edge of block 26 in Figs. 2 and 11 is marked *b*. In Fig. 14 I have shown diagrammatically both of these lower edges *a* and *b* in their proper positions, and have connected their ends with the ends of the corner line *c* at the top of the block, which is the same in both cases, by lines *d* and *e*. Line *g* connects the lower ends of lines *a* and *b*. The resulting wedge-shaped figure, illustrated by itself in Fig. 14, represents the saving in refractory at each corner of the lining when the lining of the present invention, shown in Fig. 2, is used as compared with the lining of Fig. 7, and the consequent increased capacity of the hot top for molten metal. These figures also provide a visual demonstration of the fact that the bulk of this added capacity occurs at and near the bottom of the hot top where it is of the greatest value.

20 It will be observed therefore that by putting the taper on the side blocks rather than on the corner blocks as formerly, I have increased the capacity of the hot top, principally in the lower portion thereof, and have consequently accomplished a valuable improvement. Furthermore the change is effected without any increase in the number of different lining blocks, all eight of the corner blocks being identical.

Having thus described my invention, I claim: 30

1. In a hot top, a generally rectangular casing with inner upwardly tapered surfaces and a ledge extending inwardly from its lower end, a lining therefor of refractory material supported by said ledge, said lining comprising corner elements having straight sides extending in parallel directions, and said lining also comprising side elements having upwardly tapered side edges. 35

2. In a hot top, a generally rectangular casing having inner surfaces tapered upwardly and a ledge extending inwardly from its lower end, a lining therefor of refractory material supported by said ledge, said lining comprising corner elements with beveled lateral edges, said lateral edges extending in parallel directions throughout 45 their lengths, said lining comprising also side elements with beveled edges adapted to fit the beveled edges of the corner elements, said side elements being tapered upwardly.

3. In a hot top, a generally rectangular casing 50 having inner walls tapered upwardly and a ledge extending inwardly from its lower end, a lining therefor of refractory material supported by said ledge, said lining comprising corner elements with flat inner faces of rectangular shape 55 and beveled side edges, and comprising side elements having flat inner faces in the form of symmetrical trapezoids with their lower edges longer than their upper edges, and having beveled side edges complementary to the beveled side 60 edges of the corner elements.

WALTER W. URMETZ.
